JOSEPH WILLIAM ISHERWOOD AND WILLIAM ISHERWOOD, OF RAGGLES WOOD,
CHISLEHURST, ENGLAND

COVER FOR HATCHES

Application filed December 11, 1931, Serial No. 580,449, and in Great Britain May 29, 1931.

This invention relates to covers for hatches of floating vessels and has for its object to provide an improvement over the constructions disclosed in our U. S. Letters Patent No. 1,679,526 granted August 7, 1928 entitled "Hatch cover".

Referring to the accompanying drawings forming a part of this specification in which like reference characters designate like parts in all the views,

Fig. 1 is a top plan view of a hatch with different types of cover sections applied to the bays of the right hand half, the left hand half being uncovered;

Fig. 2 is a longitudinal sectional view in diametric form of a hatch with applied covers;

Fig. 3 is a transverse sectional view in diagram and illustrating the two types of covers also shown in Fig. 1;

Fig. 4 is also a transverse sectional view taken at a web which is shown in elevation, the covers being omitted from this figure;

Figs. 5 and 6 are detail sectional views through a web illustrating the manner of securing cover sections in place;

Figs. 7 and 8 are transverse sectional details illustrating the mounting and securing of the V-shaped securing bars upon the web; and

Figs. 9 and 10 are top plan views of the construction shown of Figs. 7 and 8 respectively.

Referring to the drawings, the hatch cover is formed by a plurality of sections 1, which may, as shown in Figures 1 and 3, be either formed with corrugations or with plane surfaces, the corrugated construction being illustrated on the left hand half of Figure 3 and the second bay of Figure 1, and the plane construction being illustrated on the right hand half of Figure 3 and in the first bay of Figure 1. These hatch sections are secured in position by V-shaped securing bars 2, which are arranged over one or more hatch webs 23 fitted either transversely or longitudinally as desired. The sloping sides of the V-shaped bars 2 engage similarly inclined sides formed on the hatch cover sections, and the bars are secured in position by

bolts 3 and washers 4 which extend into recesses 5 formed conjointly by abutting ends of adjacent bars. The ends of the outermost bars 2 are bevelled as shown, more particularly in Figure 7, and extend under an inclined face formed on a block 6 secured to the hatch coaming 7. Thus, when the V-shaped bars are placed in position and secured by the bolts, the hatch cover sections are positively locked against movement. As particularly illustrated in Fig. 8 it will be seen that the open end of the V-bar 2 is filled with a block, the securing being in any convenient manner as by welding, and this block has a portion which extends beyond the limit of the V-bar. This extending portion has a reduced vertical dimension and has preferably formed in its outermost surface a semi-circular groove into which may fit the bolt 3. Thus it will be seen that when two V-bars with similar filler blocks are placed end to end as shown in Fig. 8, the reduced dimension of the filler blocks forms the recess 5 for containing the head of the bolt 3 so that no portion of the bolt extends above the top surface of the closed hatch. Further by having the semi-circular grooves in the ends of the filler blocks which are engaged by a bolt, lateral displacement of the ends of the V-bar 2 is prevented, and a more even distribution of lateral pressure is exerted on both sides of the V-bar against the contacting cover sections, when said V-bar is forced downwardly by screwing the bolts 3 into the upper portion of the underlying web 23.

The hatch cover sections may be provided with packing material such as greased hemp which is secured to one section and is compressed between that section and an adjacent section.

It is obvious that those skilled in the art may vary the details of construction as well as arrangements of parts without departing from the spirit of the invention, and therefore it is not desired to be limited to the foregoing except as may be required by the claims.

What is claimed is:—

1. In a hatch the combination of a cover comprising a plurality of small sections; a

bar wedgingly engaging the end surfaces of a plurality of said sections, said bar having a recessed end adapted to coact with a similarly recessed end of an adjoining bar; and 5 means to move said bar and the adjoining bar into the plane of said sections to lock the latter, said means lying within said recessed ends.

2. In a hatch provided with web framing 10 the combination of a cover comprising a plurality of small sections; bars supported by said framing, each bar adapted to secure a plurality of said sections; and single means operating transversely of said bars to move 15 a plurality of said bars into the plane of said sections to lock the latter.

3. In a hatch provided with web framing 20 the combination of a cover comprising a plurality of small sections; bars supported by said framing, each bar adapted to secure a plurality of said sections, two of said bars having their ends in substantial abutment; and screw means operating transversely of 25 said bars to move the abutting bars into the plane of said sections to lock the latter.

4. In a hatch provided with web framing 30 the combination of a cover comprising a plurality of small sections; bars supported by said framing, each bar adapted to secure a plurality of said sections two of said bars having their ends in substantial abutment; and single means operating transversely of 35 said bars to move the abutting bars into the plane of said sections to lock the latter.

5. In a hatch provided with web framing 40 the combination of a cover comprising a plurality of small sections; a plurality of bars supported by said framing each bar adapted to secure a plurality of said sections; a block fitted to an end of one of said bars; and means operating through said block to move 45 a plurality of said bars into the plane of said sections to lock the latter.

6. In a hatch provided with web framing 50 the combination of a cover comprising a plurality of small sections; a bar supported by said framing and adapted to secure a plurality of said sections; a block fitted to an end of said bar and having a reduced end portion establishing a recess; and means operating 55 transversely of said bar to move said bar into the plane of said sections to lock the latter, said means lying within said recess.

7. In a hatch provided with web framing 60 the combination of a cover comprising a plurality of small sections; bars supported by said framing, each bar adapted to secure a plurality of said sections; and single means to move a plurality of said bars into the plane 65 of said sections to lock the latter.

8. In a hatch provided with web framing 70 the combination of a cover comprising a plurality of small sections; bars supported by said framing, each bar adapted to secure a plurality of said sections; and single means 75

operating transversely of a bar to move a plurality of said bars into the plane of said sections to lock the latter.

In testimony whereof we affix our signatures. 80

JOSEPH WILLIAM ISHERWOOD.
